APPARATUS FOR FORMING SLIP-SEALS ON OP-
POSITIVE ENDS OF BELL-ENDED SEWER TILE

Roscoe F. Peterson, Eaton Rapids, Mich.

Application December 27, 1954, Serial No. 477,855

11 Claims. (Cl. 25—39)

The present invention relates broadly to the forming of slip-seal joints, and in its specific phases to an apparatus for use in casting alined slip-seals at the opposite ends of a sewer tile.

Tile of the glazed, bell-ended type are commonly used in the laying of sewer lines. When such tile are used for this purpose, the joints between them have to be sealed to prevent leakage as well as ingress of roots which in time will plug a tile line. The universal procedure currently used in forming such joints involves separately pouring a mastic slip-seal joint with a tapered face separately and independently on each end of the tile and then when the tile is laid, a sealant, such as asphalt or the like, is swabbed over the joint to be made with these slip-seals and the two tiles put together with the small or spigot end of one tile fitting into the hub or bell end of the other tile. Theoretically, this is a very practical procedure but the current practice of independently forming the seal on each end of a tile results in non-coaxial seals wherein the joints do not properly fit and as a result there is leakage at the joint or, when such non-axial joints are tightly fitted, there is an uneven row of sewer tile when laid. The reason for this is that seldom is there a sewer tile which is perfect. In other words, instead of being perfectly round, they turn out to be slightly elliptical or egg-shaped and, still further, the bell end of same is not only non-round but more often than not it is not in a plane truly perpendicular to the longitudinal axis of the tile. The difficulties of making tight joints under those conditions has led some cities to require that the joints between sewer tile be made and the mastic poured in place in the bottom of the trench in order to get a straight sewer with better joints. Such, however, is an impossible situation where there is water in the trench since that prevents the casting of joints in this manner. It was a recognition of these problems and unsolved difficulties which led to the conception and development of the present invention.

Accordingly, among the objects of the present invention is the provision of an apparatus which makes possible the pouring of truly alined slip-seal joints on both ends of a tile or the like while the tile is held by the machine.

Another object is to provide a machine for use in the forming of alined slip-seal joints on sewer tile wherein such machine has self-adjusting members in its upper and lower portions which aline the tile for the upper and lower slip-seals before the latter are poured.

A further object is to produce a slip-seal forming machine which is of rapid action type facilitating the formation of slip-seal joints on sewer tile or the like.

A still further object is to provide a slip-seal forming machine wherein the upper and lower members are pre-aligned and adapted to receive and center a sewer tile or the like before the mastic used in the slip-seal is poured.

A further object is to provide a slip-seal forming machine for sewer tile or the like which has adjustable

2

tile alining members adapted to aline the tile regardless of whether it is moderately out of round at either end and also regardless of whether the bell of the tile is out of true perpendicular to the axis of the tile.

5 A further object is to provide a centering means at each end of a slip-seal forming machine for bell-ended sewer tile or the like wherein there is a floating plate in both the upper and lower portions of the machine adapted to form a substantially tight joint on both the outer face of the lower end of the tile and on the inner face of the bell end of the tile so as to stop or at least substantially stop the flow of slip-seal forming mastic when same is poured to form the matching seal on both ends of the tile.

10 15 A further object is to provide means for rapidly chilling a hot poured slip-seal joint in order to speed up the formation of same.

Still further objects and advantages of the present invention will appear as the description proceeds.

20 To the accomplishment of the foregoing and related ends, the invention, then, consists of the means of forming slip-seal joints as hereinafter fully described and particularly pointed out in the claims, the annexed drawings and the following description setting forth in detail 25 certain means of carrying out the invention, such disclosed means illustrating, however, but one of the various ways in which the principle of the invention may be used.

In the annexed drawings:

30 Figure 1 shows a side elevational view of a preferred form of apparatus for producing alined slip-seal joints on the opposite ends of a bell-ended sewer tile or the like.

Figure 2 shows a top view of the apparatus illustrated in Figure 1.

35 Figure 3 shows a section view of the lower portion of the apparatus at the bottom of the tile with a slip-seal in place, as taken along the line 3—3 of Figure 4, looking in the direction of the arrows.

Figure 4 shows a top view of the lower portion of the apparatus with the tile in place and centered ready for casting the slip-seal on the spigot end of the tile.

40 Figure 5 shows a section view of the upper portion of the apparatus at the top of the bell-ended tile with a slip-seal in place, as taken along line 5—5 of Figure 6, looking in the direction of the arrows.

45 Figure 6 shows a top view of the upper portion of the apparatus with the tile in place and centered ready for casting the slip-seal in the bell end of the tile, the supporting spider portion being omitted for clarity of illustration of the other parts.

50 Referring more particularly to Figures 1 and 2 of the drawings, a preferred form of the apparatus of the present invention involves the use of a base 1 on which is mounted a hollow pedestal 2 carrying on its upper end a head 3 anchored in conventional manner on said pedestal. Mounted on the pedestal 2 between base 1 and head 3 is an adjustable member 4 which has gripping means such as bolts 5 for holding same firmly at various elevations on pedestal 2. Such pedestal is also provided with a rib or key 6 which fits a matching groove (not shown) in adjustable member 4. This type of construction makes possible straight line movement up and down when the adjustable member is moved on pedestal 2.

55 60 65 70 The outer end of adjustable member 4 is provided with a housing 7 which is preferably hollow and provided with conventional upper and lower openings 8 and 9 through which a spindle 10 closely but slidably fits. At the rear edge of this spindle there is provided a rack 11 with a gear 12 in mesh with same. This gear is mounted on a cross shaft 13 which extends through the side of housing 7 and has conventionally fastened on the outer end of same an operating member 14 which may

be of any suitable type, such as hand operated through the use of projecting arms 15.

Head 3 is also preferably made of hollow construction and provided with aligned upper and lower openings 16 and 17 for guiding spindle 10 in its endwise movements. Inside of head 3 is preferably provided a pair of rollers 18 and 19 mounted on stub shafts 20 and 21. Passing over these rollers is a chain 22, one end of which is fastened to an anchor member 23 mounted on spindle 10. The other end of chain 22, which passes over roller 18, hangs down into hollow pedestal 2 and has fastened in its lower end a counterweight 24. This counterweight is preferably of a size adapted to counterbalance the weight of spindle 10 and the upper slip-seal forming assembly 25 which is conventionally fastened in fixed position on the lower end of spindle 10. It is thus clear that by rotating operating member 14 through the use of projecting arms 15 or the like, the upper slip-seal forming assembly can be easily raised or lowered as required.

The upper slip-seal forming assembly 25, Figures 5 and 6, is carried on spindle 10 by means of a spider 26, the legs 27 of which are welded or otherwise joined to ring member 28, the outer face of which tapers inward toward the lower end of same at an angle of approximately three degrees. Welded or otherwise fastened on the inner face of ring member 28, preferably about mid-height of same, are three supporting brackets 29 which are drilled and threaded for studs 30 which in turn pass through a tiltable plate 31 and which plate is held against the heads of studs 30 by means of compression springs 32. It is thus to be seen that when ring 28 passes down into the bell 33 of tile 34, the side edges of tiltable plate 31 will first come up against the shoulder within the bell as is shown in Figure 5. If this shoulder is not perfectly in alignment with a plane perpendicular to the axis of the tile, the tiltable plate 31 will rectify such situation and rest in tilted position on the shoulder within the tile bell, for a purpose to be hereinafter set forth.

In the center of tiltable plate 31 there is provided an opening for bolt 35 on the upper end of which is fastened an operating arm 36 in any convenient manner, such as by means of a pin 37. Bolt 35 is freely rotatable in opening 38 through plate 31 and on the lower end of bolt 35 there is mounted a plate 39 which may be held against rotating on bolt 35 by means of a key 40, and adjusted endwise thereon by means of a nut 41. Pivotally mounted on plate 39 by means of studs 42 are three centering links 43, the outer ends of which are supported and held substantially free from sidewise motion by means of a pair of studs 44 and 45. Each of these centering links is preferably provided at its outer end with a tapered edge outer shoe member 46. The centering links 43, as is shown in Figure 6, are mounted off center plate 39 so that when forced down into the slightly smaller diameter top of the main bore of a tile they will rotate plate 39 in clockwise direction, Figure 6, against the tension of tension spring 47, one end of which is anchored to a pin 48 on operating arm 36 and the other end to a pin 49 on the top of tiltable plate 31. A stop plate 50 fastened to tiltable plate 31 by means of a stud 51 acts to support the assembly in starting position ready for insertion into the top or bell portion 33 of tile 34.

Mounted on the upper face of base 1 of the assembly is a lower slip-seal forming assembly 52. This assembly has a lower ring member 53, Figures 3 and 4, the inner face of which is tapered inward towards its bottom, preferably at an angle of approximately three degrees. This ring may be mounted flush on base 1, Figure 1, but is preferably fastened in conventional manner, as shown in Figures 3 and 4, on three supporting arms 54, the outer ends of which are provided with bolt holes 55 for use in fastening the lower slip-seal forming assembly 52 on base 1 in axial alignment with upper slip-seal forming assembly 25. The inner ends of these supporting arms 54 are drilled and threaded for studs 56

which in turn have loosely mounted thereon a lower tiltable plate 57 with compression springs 58 on said studs between supporting arms 54 and tiltable plate 57. These springs thus allow the plate to tilt and closely fit the lower end of spigot 59 of tile 34 for a purpose to be hereinafter set forth. Approximately at the center of tiltable plate 57 same is provided with an opening 60 which closely but freely fits bolt 61. The lower end of that bolt carries an operating arm 62 anchored in fixed position thereon in conventional manner, for instance by means of a pin 63 and a nut 64. A stop member 65 held in place on tiltable plate 57 by a stud 66 acts as a bumper for operating arm 62, which is normally held up against same by means of a tension spring 67, one end of which is connected to a pin 68 fastened to operating arm 62, while the other end of tension spring 67 is fastened to a pin 69 connected to the under face of tiltable plate 57. At the upper side of tiltable plate 57 there is fastened on bolt 61, for rotation therewith, a plate 70. The fastening of plate 70 on bolt 61 may be accomplished in any conventional manner, such as by means of a key 71. Eccentrically joined to plate 70 by means of studs 72 are three centering links 73, each of which has a tapered end shoe member 74 adapted to contact the inner face of the spigot 59 of tile 34 to center same in lower ring member 53. Each centering link 73 is guided in its endwise movements by a pair of studs 75 and 76 which also hold down and stabilize the centering links 73 when the tile 34 is removed from the assembly.

Since the mastic forming the lining 77 in the bell 33, and the ferrule 78 on spigot 59 of tile 34 is generally of asphalt base type and is applied hot, upper ring member 28 and lower ring member 53 are preferably made hollow for the reception of a cooling fluid, such as cold water, to quickly set up the mastic and thus increase the output of the machine. If desired the cooling fluid can be delivered to the assembly by means of a supply pipe 79, Figures 1 and 2, connected to the inlet of lower ring member 53 by means of an inlet pipe 80, and to the inlet of upper ring member 28 by means of an inlet hose 81 and nipple 82. At the opposite side of the assembly there is provided an exhaust pipe 83 connected to the outlet of lower ring member 53 by means of an outlet pipe 84, and to the outlet of the upper ring member by means of an outlet nipple 85 and an outlet hose 86.

To use the present invention, the tapered outer face of the upper ring member 28 and the tapered inner face of lower ring member 53 are coated with a lubricating material such as wet soapstone. The upper slip-seal forming assembly is then raised by appropriately rotating operating member 14, Figure 1, and tile 34 is set in place with its spigot 59 centered within ring 53 on the lower tiltable plate, and resting on lower tiltable plate 57 and then the upper slip-seal forming assembly 25 is lowered into place within the bell 33 until its tiltable plate 31 is in contact with and resting on the inner shoulder of bell 33. With the cooling fluid, such as cold water, flowing through upper and lower ring members 28 and 53, the apparatus is ready for the pouring of the hot mastic lining of the bell 33 and ferrule of the spigot 59 of the tile 34. At the end of the casting procedure when the mastic has hardened the upper slip-seal forming assembly 25 can be raised, and the tile 34 with its lined lining and ferrule can be removed and replaced with another tile to repeat the cycle. It is thus to be seen that tiltable plates 31 and 59 act as a backstop for the hot mastic and hold it against substantial through flow and waste.

The tile 34 thus provided with the lined lining 77 and ferrule 78, which are of mating size and taper, is adapted for laying with like tile to form a tile line such as a sewer, or the like, in the bottom of a trench even though there be some water in the trench. While these tile can be laid without further treatment, it is preferred that the mating surfaces of the lining and ferrule be

swabbed with a suitable sealant before being pushed tightly together, one after another, to form the tile line. This sealant which may be of tarry or liquid asphalt type, or even of mastic solvent type, causes the lining and ferrule to join in their mating surfaces so that once they have set up it is practically impossible to get them apart and a watertight joint is formed.

From the foregoing it will be seen that a novel and advantageous type of apparatus for forming slip-seal joints in the bell end and on the spigot end of sewer tile or the like has been provided, and new methods in connection with same, have been disclosed for attaining the desired ends. However, attention is invited to the possibility of making variations to same within the spirit and scope of the present invention. While for convenience the apparatus and method involved have been described and set forth in terms of an upright mounted apparatus, it is not limited to that position, even though it is a preferred one. The directional terms such as "upper," "lower," "top," "bottom," et cetera, are accordingly to be considered as relative only, and not limiting on either the apparatus, method, or product involved.

Other modes of applying the principle of my invention may be employed instead of the one explained, change being made as regards the means and methods herein disclosed, provided those stated by any of the following claims or their equivalent be employed.

I therefore particularly point out and distinctly claim as my invention:

1. A machine for forming slip-seals on the opposite ends of an article such as a bell-ended sewer tile, which comprises an upper slip-seal forming means, a lower slip-seal forming means, a base for the latter slip-seal forming means, a pedestal laterally offset with respect to both of said means rising from said base, a head extending from said pedestal above both of said slip-seal forming means, a spindle rising from said upper slip-seal forming means slidably guided in said head, said upper and lower slip-seal forming means being in axial alignment with each other, means adjustably carried by said pedestal located intermediate said upper slip-seal forming means and head for adjusting the space between said upper and lower slip-seal forming means to facilitate placing said tile in position to receive said slip-seals, and to remove the same after said slip-seals are finished, and resiliently biased means carried by both said upper and lower slip-seal forming means insertable within the ends of the sewer tile for truing the ends of the sewer tile with respect to the slip-seal forming means regardless of irregularities in the tile ends.

2. A machine for forming alined slip-seals as set forth in claim 1, wherein said upper and lower slip-seal forming means include tapered face members having substantially identical tapers of a size to form slip-seals with mating size faces on the opposite ends of the tile, and tiltable means adjacent the lower end of each of said tapered face members adapted to form a substantially tight joint between said tapered face members and said tile at the lower end of each of said slip-seals.

3. A machine for forming alined slip-seals as set forth in claim 1, wherein said upper and lower slip-seal forming means include hollow tapered face members, and connecting means facilitating the flowing of a cooling fluid through said tapered face members, said tapered face members having substantially identical tapers of a size to form slip-seals with mating size faces on the opposite ends of the tile.

4. A machine for forming mating slip-seals on the opposite ends of an article such as a bell-ended sewer tile, which comprises a base, a pedestal mounted on and extending upward from said base, a head means mounted on the upper end of said pedestal, an endwise adjustable means mounted on the upper portion of said pedestal below said head means and extending over said base, an upper slip-seal forming means, a spindle member

connected to the upper end of said upper slip-seal forming means, said head means and said adjustable means mounted on said pedestal acting through said spindle to guide said upper slip-seal means in its endwise movements, means on said adjustable means for engaging said spindle member for raising and lowering said upper slip-seal means relative to said adjustable means, a lower slip-seal forming means mounted on said base, said upper and lower slip-seal forming means being in alinement, 5 said upper and lower slip-seal forming means including members with truncated cone shaped seal forming faces having substantially identical small angle tapers inclined in the same direction to form mating face seals with the seal in the bell-end of the tile flaring outward, said 10 members with the truncated cone faces being hollow, connecting means facilitating the flowing of a cooling fluid through said hollow members, a plate member mounted on each of said hollow members, each of said plate members being slightly smaller than, within, and adjacent 15 the lower end of the corresponding hollow member, means for tiltably mounting said plate members for movement relative to said hollow members to facilitate said plate members substantially sealing on an end portion of said tile, a self-adjusting tile end centering means 20 for each of said plate members, and means for mounting said self-adjusting tile end centering means on the adjacent sides of said plate members in position to engage the inside of the main bore of the tile adjacent its ends.

5. In a machine for forming slip-seals, a ring for molding a side face of a slip-seal, a plate for seating contact with a wall of a tile perpendicular to its longitudinal axis, centering elements pivoted to said plate adapted to extend into and engage the bore wall of the tile, means loosely and resiliently holding said plate on said ring in a manner permitting tilting of said plate, to enable better engagement of same with said first-mentioned wall, and a spring actuated rotatable mechanism pivotally mounted on said plate and pivotally connected to said centering elements for resiliently urging them toward bore wall-40 engaging position.

6. In a machine for forming slip-seals, a plate for seating contact with a wall of a tile perpendicular to its longitudinal axis, a bolt means passing loosely through said plate permitting tilting of the latter to enable better engagement with said first-mentioned wall, a second plate, 45 said second plate being turnable with said bolt means, centering elements pivoted to said second plate, means on the first plate to guide the centering elements in paths non-radial with respect to the bolt means into engagement with the bore wall of the tile, and means mounted by one of the plates and connected to the other plate urging movement of the centering elements toward bore wall-engaging position.

7. A machine for forming slip-seals on the opposite ends of an article such as a bell-ended sewer tile, which comprises an upper slip-seal forming means, a lower slip-seal forming means, a base for the latter slip-seal forming means, a pedestal laterally offset with respect to both of said means rising from said base, a head extending from said pedestal above both of said slip-seal forming means, a spindle rising from said upper slip-seal forming means slidably guided in said head, said upper and lower slip-seal forming means being in axial alignment with each other, means adjustably carried by said pedestal located intermediate said upper slip-seal forming means and head for adjusting the space between said upper and lower slip-seal forming means to facilitate placing said tile in position to receive said slip-seals, and to remove same after said slip-seals are finished, and at 55 least one of said slip-seal forming means including a tapered face member, and a plate member slightly smaller than, within, and adjacent the lower end of said tapered face member, and means for tiltably mounting said plate member for movement relative to said tapered face

member to facilitate said plate member substantially sealing on an end portion of said tile.

8. A device as set forth in claim 7, including means for cooling the hot mastic material applied to the ends of said sewer tile adjacent said slip-seal forming means.

9. A machine for forming slip-seals on the opposite ends of the article such as a bell-ended sewer tile, which comprises an upper slip-seal forming means, a lower slip-seal forming means, a base for the latter slip-seal forming means, a pedestal laterally offset with respect to both of said means rising from said base, a head extending from said pedestal above both of said slip-seal forming means, a spindle rising from said upper slip-seal forming means slidably guided in said head, said upper and lower slip-seal forming means being in axial alignment with each other, means adjustably carried by said pedestal located intermediate said upper slip-seal forming means and head for adjusting the space between said upper and lower slip-seal forming means to facilitate placing said tile in position to receive said slip-seals, and to remove same after said slip-seals are finished, and at least one of said slip-seal forming means including a tapered face member, a plate member slightly smaller than, within, and adjacent the lower end of said tapered face member, means for tiltably mounting said plate member for movement relative to said tapered face member to facilitate said plate member substantially sealing on an end portion of said tile, a self-adjusting tile end centering means, and means for mounting the latter on said plate member.

10. A machine for forming mating slip-seals on the opposite ends of an article such as a bell-ended sewer tile, which comprises a base, a hollow pedestal mounted on and extending upward from said base, a member mounted on the upper portion of said pedestal for adjustment endwise of the latter, a hollow head above said member projecting from said pedestal, said member and

5 head extending over said base, an upper slip-seal forming means, a spindle rising from the latter slideable in said member and said head, counter-balancing means for said upper slip-seal forming means primarily located within 10 said pedestal and said head, means on said adjustable member for raising and lowering said upper slip-seal forming means, a lower slip-seal forming means mounted on said base, said upper and lower slip-seal forming means being in alignment with each other and of matching sizes 15 so as to form coaxial mating size and shape slip-seals, with the slip-seal in the bell end of the tile being in the form of a lining member and that on the other end of the tile in the form of a ferrule, at least one of said slip-seal forming means including a member with a truncated cone-shaped seal forming face, and a plate member slightly smaller than and adjacent the lower end of said truncated cone-shaped seal forming face member, and means for tiltably mounting said plate member for movement relative to said truncated cone-shaped seal forming face member to facilitate said plate member substantially sealing on an end portion of said tile.

11. The device as set forth in claim 10, including a self-adjusting tile end centering means, and means for mounting the latter on said plate member.
